HYDRAULIC JACK

Filed May 5, 1944

UNITED STATES PATENT OFFICE

2,464,254

HYDRAULIC JACK

Joseph J. Mueller, St. Joseph, Mich., assignor to
 Auto Specialties Manufacturing Company, St.
 Joseph, Mich., a corporation of Michigan

Application May 5, 1944, Serial No. 534,210

1 Claim. (Cl. 60—52)

1

This invention relates to hydraulic jacks, and while the invention is capable of broad adaptation to a jack of the general principles herein illustrated, the invention is for purposes of illustration, but not by way of limitation, shown as applied to a jack of the construction set forth in my co-pending application Serial No. 468,768, filed December 12, 1942, now patent No. 2,412,414, issued December 10, 1946.

Therefore one of the objects of the present invention is to provide a jack which is an improvement on the jack disclosed in my before mentioned application, and wherein a valve seat is formed in the upper end of the central bore of the stationary ram, and a valve rod and valve are mounted in the underside of the top portion of the slidable ram cylinder so that when the cylinder is raised to a predetermined height the valve will cut off the pressure fluid to the underside of the ram cylinder, whereby to prevent injury to the jack if the hydraulic pumping action be continued beyond such predetermined lifting range.

Yet another object of the invention resides in providing a jack having an upstanding stationary ram and a relatively slidable ram sleeve enveloping the ram, the top surface of the ram sleeve being provided with a threaded plug, the head of which is arranged so that pressure against the underside of the ram sleeve normally tends to seal the plug more tightly, the plug being provided with a central threaded aperture to receive and carry a depending valve rod co-operating with a sleeve provided with a complementary valve seat therein formed in the upper portion of the central bore of the stationary ram cylinder, whereby to cut off further fluid pressure against the underside of the ram sleeve at a predetermined point in its elevation.

These and other objects of the invention will be apparent from the following specification, when taken in connection with the accompanying drawing, wherein:

Figure 1 is a perspective view of one form of the invention;

Figure 2 is a sectional view taken on the line 2—2 of Figure 1;

Figure 3 is a sectional view taken on the line 3—3 of Figure 2;

Figure 4 is an enlarged section taken through the oil reservoir, showing the by-pass valve; and

Figure 5 is a section corresponding to Figure 2, but showing the cut-off valve in its uppermost position with respect to the stationary ram cylinder.

2

Referring now to the drawings in detail, the particular jack with which the invention is illustrated embodies a base 2 which is provided centrally with an upstanding wall 4 providing a central well. The circular inner faces of the upstanding wall 4 are threaded as at 6. Onto this threaded portion screws a stationary ram 8 having a central longitudinally disposed liquid passageway 10. An elongated hollow ram cylinder in the form of the sleeve 12, preferably formed of malleable iron, encloses the stationary ram 8. This shiftable ram cylinder 12 is provided with an inwardly extending shoulder 14 at its top and the upper surface of the ram is suitably knurled or fashioned as at 16 to grip the load to be lifted. The top of the ram cylinder is preferably provided with a screw threaded opening into which is threaded the plug 20. This plug is provided with a head 22 on its inner end and with a hexagonal recess 24 in its outer or top end. By this arrangement the fluid pressure within the ram cylinder 12 tends to force the plug tightly to its seat to prevent leakage. The ram cylinder 12 at its bottom is suitably threaded as at 26 to receive a packing 32 which lies between the bottom of the stationary ram 8 and the inner smooth surface of the ram cylinder 12. At its outer bottom end the ram cylinder is provided with a foot lift step 34 which forms a second load receiving surface. The bottom of the ram 8 is recessed as at 36 and joins the internal passageway 10 formed centrally of the ram. It is particularly to be observed that there is a minimum of space between the external smooth wall of the ram and the internal smooth wall of the ram cylinder 12, other than that space demanded in order to permit the ram cylinder 12 to elevate or depress relatively to the stationary ram 8. By means of this construction it will be noted that any oil which leaks into this space between the external vertical face of the ram 8 and the internal vertical face of the ram cylinder 12, on elevation of the ram cylinder will be permitted to escape upwardly to the space between the top of the stationary ram and the underside of the ram cylinder 12 and will not be forced downwardly past the packing 32. In this manner escape or seepage of the oil to an external surface of the ram cylinder is precluded.

Cast integrally with the upstanding wall 4 of the base is an oil reservoir 38. This reservoir is preferably cylindrically shaped and is disposed laterally of the central axis or passageway 10 of the upstanding ram 8. The cylindrical

reservoir extends substantially from one side of the base to the other, as indicated in Figures 1 and 3, and this cylinder is provided with a threaded opening at each end, such as 40 and 42, to receive threaded plugs 44 and 46 whereby to facilitate the casting of the reservoir as well as to permit the filling of the same with suitable liquid, preferably oil. The plugs 44 and 46 are countersunk at their outer ends in a hexagonal manner to permit the removal and insertion of the same.

A plunger pump cylinder is cast integrally with the oil reservoir. As shown in Figures 2 and 3, the walls 48 are internally formed centrally of the reservoir, extending vertically downwardly as indicated in the above mentioned figures. At the top the pump cylinder casting is shouldered as at 50 to receive a threaded packing plug or ring 52 which serves to hold suitable packing 54 in position to prevent leakage outwardly around the pump piston. A pump piston 56 is adapted to be reciprocatingly mounted within this cylinder 48 and to this end the pump piston is provided at its outer end with a cross bore 58 in which a pin 60 is disposed, and the pump piston having at its inner or opposite end a threaded shank to which is attached a nut 57 which supports a collar 59 being surrounded by a leather pump washer 61, as shown in Figure 3. The opposite ends of the pin 60 lie in registering apertures 62 and 64 of ears 66 and 68 of an actuator 70 pivoted as at 72 to the outer end of the links 74 which are in turn pivoted by means of the pin 76 to the ears 82 integrally cast on the top surface of the reservoir 38. The actuator 70 is provided with a socket 80 in which an operating handle 88 may be inserted whereby upon reciprocation of the handle in a vertical plane the high pressure pump will be actuated in a manner well known in the hydraulic jack art to draw liquid from within the interior of the reservoir 38 through the cast passageway 90 past the ball valve 92. This ball valve, as shown, is normally held by means of a spring 94 on its seat 96. The liquid will be drawn inwardly by an upward movement of the piston 56 into the high pressure cylinder chamber 39 and then upon downward movement of the piston 56 the ball 92 will be pressed against the seat and the liquid will thence be transferred past the larger ball 98, thence through the transversely extending cast opening 100, thence through channel 102-104 into the recess 36 of the ram 8, thence up the longitudinal passageway 10 of the ram to cause the upward projection of the ram cylinder 12. The ball valve 98 is normally pressed to its seat by means of the spring 99.

A diagonally disposed passageway 106 connects the passageway 102 in the base of the jack with the reservoir and the upper portion of this cross passage 106 is provided with a valve seat 108 which is normally closed by means of a valve formed on the inner end of a valve stem 110 which by means of the threads 112 engages corresponding threads on a sleeve 114 cast integrally with the inner walls 116 of the reservoir. Suitable packing 118 held in position by means of a threaded thimble 120 prevents leakage past this valve stem 110. Rotation of the outer end of the handle 122 of this valve stem opens communication between the reservoir and the passageway 102 so as permit the passage of liquid directly from the stationary ram 8 back into the reservoir whereby to release the pressure in the space between the ram and ram cylinder to permit the descent or downward inward movement of the

ram cylinder 12 relative to the ram 8 and the base. It will be noted that by this arrangement and by forming the passageway 106 directly within the inner wall of the oil cylinder, leakage is precluded since the oil in escaping must pass directly into the oil reservoir.

It will be noted that passage 102 is closed at its outer end by a suitable threaded plug 103, and it will be likewise noted that the passage 100 is closed by another threaded plug 124, and in order to give access to this plug the bottom portion of the casting is hollowed out arcuately as at 126.

The front wall of the reservoir 38 is provided with spaced outstanding ears 128 to which are pivoted the opposite ends of a handle 130 for lifting the jack at its base.

It will be noticed from Figure 3 that the passageway 90 within the oil reservoir is arranged so that the end 91 of this passageway terminates relatively close to the vertical end wall 93 of the oil reservoir near fill plug 44. By this arrangement the jack can be positioned for horizontal operation on one of its sides, whereby reservoir plug 44 is downward, and still draw fluid through port 91 from the lowermost portion of the reservoir.

In accordance with the improved features of this invention, means is provided in association with the ram and ram cylinder, and preferably the central oil conduit 10, for limiting the vertical lift of the ram cylinder 12 with respect to the stationary ram 8. In the construction illustrated, this comprises valve means carried by the ram cylinder and operative at a predetermined elevation of the ram cylinder to cut off the upper portion of the passageway so as to prevent liquid being forced into the space between the upper surface of the ram 8 and the undersurface of the ram cylinder 12. In the present instance this is accomplished by providing the plug 20 with a threaded hole 95 to receive an elongated valve rod 97 having on its bottom end a tapered valve 99. This valve is adapted to seat against a valve seat 101 formed in a threaded sleeve 103 which screws into a threaded internal bore 105 at the top of the oil passage 10 of the ram 8. The bottom of this passage in which the threaded sleeve 105 threadedly engages is provided with an unthreaded portion 107 having inwardly tapering walls 109 whereby to guide the valve 99 as it moves downwardly when the sleeve-like ram cylinder 12 descends. In the operation of this device, when the ram cylinder 12 reaches the position shown in Figure 5, the tapered upper wall of the valve 99 will contact the tapered seat 101 of the sleeve 103 and cut off passage 10 so that oil can no longer be forced into the space between the underside of the ram cylinder and the top of the ram. When the passageway 10 is thus cut off no further elevation of the ram cylinder is possible so that any attempt to continue the elevation of the ram cylinder will prove fruitless.

Obviously the invention is not limited to the specific details of construction disclosed herein but is capable of other modifications and changes without departing from the spirit and scope of the appended claim.

Having thus described my invention, what I claim as new and desire to secure by Letters Patent is:

In an hydraulic jack, the combination of a base, a ram stationarily projecting upwardly therefrom and having a central vertical liquid passage, a sleeve-like ram cylinder adapted to fit

over the ram, said jack having a liquid reservoir associated with the base, pumping means associated with the base including passages interconnecting the reservoir, the pumping means, and the central passage of the ram for drawing liquid from the reservoir and forcing it under pressure to the central passage of the ram, by-pass means for relieving the oil in the ram and passing it back to the reservoir, the upper portion of said vertical passage in said ram being provided with an enlargement the upper portion of which is threaded, a hollow sleeve screwing into the threads of said enlargement, the bottom inner wall of said sleeve being formed with tapering wall portions forming a valve seat, the enlargement below said sleeve being tapered conically inwardly and downwardly, the top of said ram cylinder having a central threaded opening, a plug having an external thread screwing into said opening and having a head larger than said opening and disposed internally of said cylinder to seal said opening under the pressure conditions to which the underside of said head is subjected, said plug head having a central bore and a rod-

like element mounted in the central opening of the plug head and extending downwardly through the passage through said sleeve and provided on its lower end with a tapered valve to close upon the valve seat formed by said sleeve, said tapered walls of said enlargement forming a guide to center said valve as it moves downwardly.
